UNITED STATES PATENT OFFICE.

ALBERT S. SPEIRS, OF NEW YORK, N. Y.

DESIGN FOR AN INDIAN PEACE-PIPE.

SPECIFICATION forming part of Design No. 36,669, dated December 8, 1903.

Application filed November 6, 1903. Serial No. 180,142. Term of patent 7 years.

To all whom it may concern:

Be it known that I, ALBERT S. SPEIRS, a citizen of the United States, residing at New York, in the county of New York and State of New York, have invented a new, original, and ornamental Design for an Indian Peace-Pipe, of which the following is a specification.

This invention relates to a new, original, and ornamental design for an Indian peace-pipe, as shown in the accompanying drawing, in which is represented a perspective view of a pipe, showing this new and ornamental design.

I claim as my invention—

The ornamental design for an Indian peace- 15 pipe as shown in the accompanying drawing.

In testimony that I claim the foregoing as my own I have hereto affixed my signature in the presence of two witnesses.

ALBERT S. SPEIRS.
